UNITED STATES PATENT OFFICE

162,387

COMBINED BUILDING AND DISPLAY SIGN

Samuel L. Cooper, Chicago, Ill.

Application November 12, 1948, Serial No. 149,582

Term of patent 14 years

(Cl. D13—1)

To all whom it may concern:

Be it known that I, Samuel L. Cooper, a citizen of the United States, residing at Chicago, in the county of Cook and State of Illinois, have invented a new, original, and ornamental Design for a Combined Building and Display Sign, of which the following is a specification, reference being had to the accompanying drawing forming a part thereof.

Figure 1 is a front elevational view of a combined building and display sign, showing my new design; and

Figure 2 is a plan view thereof.

The sides and rear of the sign are similar to the side shown.

I claim:

The ornamental design for a combined building and display sign, as shown and described.

SAMUEL L. COOPER.
